UNITED STATES PATENT OFFICE.

WILLIAM H. BORDEN, OF WINCHESTER, MASSACHUSETTS, ASSIGNOR TO UNITED SHOE MACHINERY CORPORATION, OF PATERSON, NEW JERSEY, A CORPORATION OF NEW JERSEY.

WIRE-REEL FOR FASTENING-INSERTING MACHINES.

1,294,384.

Specification of Letters Patent. Patented Feb. 18, 1919.

Application filed April 6, 1918. Serial No. 227,118.

To all whom it may concern:

Be it known that I, WILLIAM H. BORDEN, a citizen of the United States, residing at Winchester, in the county of Middlesex and 5 State of Massachusetts, have invented certain Improvements in Wire-Reels for Fastening-Inserting Machines, of which the following description, in connection with the accompanying drawings, is a specification, 10 like reference characters on the drawings indicating like parts in the several figures.

This invention relates to wire reels for fastening inserting machines of the type which form fastenings from wire and insert 15 them into work such, for example, as shoe stock and pertains particularly to reels of the type constructed to deliver the wire from the interior of a coil of wire.

Considerable difficulty has been experienced in supplying wire to the machines employed for inserting fastenings in shoe stock. In the early stages of the development of the art, the wire from which the fastenings were formed was supplied to the 20 machines on reels which delivered the wire from the outside of a coil of wire. The elasticity or springiness of the wire caused the rings of the coil to expand outwardly upon the withdrawal of adjacent rings with 25 the result that the length of wire being withdrawn from the reel often became entangled with expanded and displaced rings of the wire thus retarding the delivery of the wire from the reel, and because of the 30 changing resistance opposed to the withdrawal of the wire from the reel, the tension under which the wire was fed to the fastening inserting machine varied greatly, whereas it is necessary to the efficient operation 35 of such machines that the wire be delivered thereto under uniform tension to the end that the wire feeding mechanism will feed the wire an equal amount upon each 40 operation of said mechanism so that the fastenings formed from the wire will be all of the desired length. The difficulties encountered in the use of reels as previously constructed were to a large extent obviated by the reel construction shown in the patent to 45 Casgrain No. 765,650, granted July 19, 1904, which is now in use on fastening inserting machines of many types. In the operation 50 of the reel disclosed in the above patent, the wire is delivered from the interior of a 55 coil of wire, and the springiness of the wire

tends to maintain the individual coils or rings of the wire in proper place on the coil until their withdrawal therefrom, thus facilitating the uniform delivery of the wire from the coil.

The object of the present invention is to provide means whereby reels of the type disclosed in Patent No. 765,650 may be made still more efficient in operation and may be adapted to operate effectively on 60 wire of widely varying characteristics.

In carrying out the objects of the invention, I have provided improved means for guiding the wire in its withdrawal from the coil, said means being mounted for 70 movement toward and from the axis of rotation of the reel and controlled in its movements by the wire as it is withdrawn from the reel. Preferably and as shown, said guiding means is organized to brake the 75 reel upon release of the pull on the wire and to present a braking surface of a width substantially equal to the width of the inner surface of the coil and arranged to engage the inner surface of the coil adjacent to the point of withdrawal of the wire from the coil.

Other objects and features of the invention will appear as the description proceeds.

In the drawings,

Figure 1 is a plan view of a wire reel in which the invention is embodied,

Fig. 2 is a view in elevation of the reel shown in Fig. 1, and

Fig. 3 is a detail view of the member 90 which guides the wire as it is withdrawn from the reel and also operates to brake the reel upon release of the pull on the wire.

The wire reel 2 is carried by a bracket 4 which may be secured to the frame of a fastening inserting or other machine by any suitable means (not shown). In the end of the bracket 4 is seated a stud shaft 6 upon which the wire reel is rotatably mounted, antifriction devices 8 being provided for 95 facilitating the rotation of the reel. The reel 2 is formed with arms 10 extending from the central hub 12 which is loosely journaled on the stud shaft 6. The arms 10 are formed at their outer ends with extensions arranged substantially at right angles to their body portions and said extensions are merged into an annulus 14, there being thus provided a light frame which 100 can be easily rotated about the stud shaft 6. 105

The mechanism thus far described forms in itself no part of the present invention and may be embodied in various forms without departing from the principles of the 5 invention.

To the end of making the operation of the reel more efficient and in order to adapt the reel for use with wire of varying characteristics, I provide improved means for guiding 10 the wire as it is withdrawn from the reel. As shown, the wire guiding means comprises a member 16 formed with a down-turned boss 18 which is rotatably received in an opening in the member 20 which projects 15 from the bracket 4 adjacent to the opening 22 of the bracket in which the stud shaft 6 is seated. The wire guiding member 16 is preferably and as shown extended to a point adjacent to the inner surface of 20 the coil for the purpose of increasing that component of the force exerted in withdrawing the wire from the reel which tends to rotate the reel. This causes the wire to be withdrawn from the reel at a point adjacent 25 to the entrance to the wire guide 16 and thus tends to prevent the formation of sharp turns in the wire which are objectionable inasmuch as the fastenings formed from the wire by the fastening inserting 30 machine must be straight else they cannot be properly driven into the work.

The wire guiding member 16 is laterally offset at 24 and said offset portion has a surface 26 arranged to engage the interior 35 surface of the coil of wire in the reel thereby to check or brake the rotation of the reel. Although it is preferred that the braking surface 26 of the wire guide be arranged to engage the surface of the coil, it will be understood 40 that the invention in certain of its aspects contemplates that the braking surface may be arranged for engagement with a part of the reel itself.

When a pull is exerted on the wire in the 45 feeding of the wire from the reel to the fastening inserting machine, the increase of the tension of the wire causes the wire guiding member 16 to be turned on its pivot 18 in a direction away from the inner surface 50 of the coil. Such movement of the wire guiding member lessens the angle at which the wire enters the passage of the guide, thus preventing formation of sharp bends in the wire and withdraws the braking surface 55 26 from the inner surface of the coil, thereby permitting the coil to rotate freely so long as a pull is exerted on the wire to withdraw the same from the coil. When, however, the pull on the wire 60 is relieved, the spring of the wire, which, as before stated, tends to press each ring of the coil against the inner surface of the coil, will cause the wire in the passage of the wire guiding means to exert pressure on the 65 wire guiding means in a direction to move

the braking surface 26 of the wire guiding member 16 into braking engagement with the inner surface of the coil.

From the foregoing it will be understood that the wire guiding and braking member 70 16 operates automatically to prevent overrunning of the wire reel while at the same time permitting free feeding of the wire therefrom.

Preferably and as shown, the braking 75 surface 26 of the wire guiding member 16 is of a width substantially equal to the width of the inner surface of the coil and said braking surface is arranged adjacent to the point of withdrawal of the wire from the 80 coil. When pull is exerted on the wire in the feeding of the wire from the reel, the force of the pull tends to draw the wire away from the inner surface of the coil, wherefore the initial effect of the pull is to 85 move the wire slightly at the point where the length of wire between the guiding member 16 and the inner surface of the coil of wire engages the adjacent rings of the wire. During this operation, by reason of the inertia 90 of the guiding member 16, the braking surface 26 is maintained in position against the adjacent rings of the wire and tends to prevent them from being loosened or displaced by the withdrawal of the wire. 95 The pull on the wire being continued, the increased tension of the wire moves the braking surface 26 of the wire guiding member 16 away from the inner surface of the coil and maintains the wire guiding and braking member 16 free from the surface of the coil until the pull on the wire is again relieved. Due to the inertia of the parts, the rings of the coil are most likely to be displaced on the coil upon the initial exertion 100 of the pull on the wire to withdraw it from the coil. From the foregoing, it will therefore be seen that the braking surface 26 positively maintains the rings of the wire from displacement at the time when they 105 would otherwise be most likely to be displaced.

Means are preferably provided for limiting the movement of the wire guiding and braking member 16. As shown, said means 115 comprises a lug 28 extended from the boss 18 of the member 16 and a set screw 30 carried adjustably by a projection 32 extended from the bracket 4 and interposed into the path of movement of the lug 28. The set 120 screw 30 prevents the wire guiding member 16 from moving outwardly far enough to be struck by the arms 10 in the rotation of the reel.

In operating on certain kinds of wire, it 125 is desirable that means be provided to supplement the springiness or elasticity of the wire in applying the braking surface 26 to the inner surface of the coil. In such cases, means are preferably provided for urging 130

the braking surface 26 yieldingly in the direction of the surface of the coil. As shown, Fig. 3, such means comprises a spring 34 connected at one end to the pin 36 on the 5 projection 20 and at its other end to a pin 38 carried by a split sleeve 40 mounted on the end of the stud 18. The split sleeve 40 may be rotatably moved on the stud 18 to adjust the tension of the spring in accordance with the characteristics of the wire being operated upon, and said sleeve is secured in adjusted position on the stud 18 by the bolt 42.

Having fully described the invention, what 15 I claim as new and desire to secure by Letters Patent of the United States is:

1. In a device of the class described, a wire reel constructed and arranged to deliver wire from the interior of a coil of wire 20 in response to a pull on the wire, in combination with means for guiding the wire as it is withdrawn from the reel constructed and arranged to brake the reel upon release of the pull on the wire.

2. In a device of the class described, a wire reel constructed and arranged to deliver the wire from the interior of a coil of wire in response to a pull on the wire, in combination with means for guiding the 30 wire as it is withdrawn from the reel constructed and arranged to be moved by the wire into position to brake the reel when the pull on the wire is released and to be moved by the wire out of braking engagement with the reel when pull is exerted on the wire to withdraw the same from the reel.

3. In a device of the class described, a wire reel constructed and arranged to deliver the wire from the interior of a coil of wire 40 in combination with braking means movable into and out of contact with the interior surface of the coil of wire.

4. In a device of the class described, a wire reel constructed and arranged to deliver the wire from the interior of a coil of wire in response to a pull on the wire in combination with means for braking the wire reel controlled by the pull on the wire.

5. In a device of the class described, a wire reel constructed and arranged to deliver the wire from the interior of a coil of wire, in combination with means for rotatably supporting the reel and means for guiding the wire mounted for movement toward and from the axis of rotation of the reel and controlled in its movements by the wire as it is withdrawn from the coil through said guiding means.

6. In a device of the class described, a wire reel constructed and arranged to deliver wire from the interior of a coil of wire in response to a pull on the wire, in combination with means for rotatably supporting the reel and means for guiding the wire as it is withdrawn from the reel, said guiding means be-

ing fulcrumed for movement toward and from the axis of rotation of the reel and constructed and arranged to brake the reel upon release of the pull on the wire.

7. In a device of the class described, a wire reel constructed and arranged to deliver wire from the interior of a coil of wire in response to a pull on the wire in combination with means for rotatably supporting the reel, means for guiding the wire, and means for fulcruming said guiding means at a point adjacent to the axis of rotation of the reel, said guiding means being constructed and arranged to brake the reel upon release of the pull on the wire. 80

8. In a device of the class described, a wire reel constructed and arranged to deliver wire from the interior of a coil of wire, in combination with means for guiding the wire mounted interiorly of the coil of wire 85 for movement toward and from the inner surface of the coil of wire and means for limiting the movement of said wire guiding means.

9. In a device of the class described, a wire reel formed on one side and on its periphery with spaced arms and on its opposite side with an annulus connected to said arms, means for rotatably supporting said reel, said reel being constructed and arranged to deliver wire from the interior of a coil of wire through the central opening in said annulus, means for guiding the wire as it is withdrawn from the reel, means for fulcruming the wire guiding means for 100 movement toward and from the inner surface of the coil of wire, and means for limiting the outward movement of said wire guiding means to prevent said guiding means from movement into the path of 105 movement of said arms.

10. In a device of the class described, a wire reel constructed and arranged to deliver wire from the interior of a coil of wire, in combination with means for guiding the 110 wire mounted for movement toward and from the inner surface of the coil of wire, and means for urging said wire guiding means yieldingly in the direction of the inner surface of the coil.

11. In a device of the class described, a wire reel constructed and arranged to deliver wire from the interior of a coil of wire, in combination with means for guiding the wire mounted for movement toward and 120 from the inner surface of the coil of wire, means for urging said wire guiding means yieldingly in the direction of the inner surface of the coil, and means for regulating the force exerted by said last-mentioned 125 means in accordance with the character of the wire being operated upon.

12. In a device of the class described, a wire reel constructed and arranged to deliver the wire from the interior of a coil 130

of wire, in combination with means for braking said reel controlled by the wire as it is withdrawn from the reel, said means having a braking surface of a width substantially equal to the width of the inner surface of the coil of wire and constructed to engage the inner surface of the coil at a point adjacent to the point of withdrawal

of the wire from the coil so as to maintain the rings of the wire against the body of the coil upon initiation of the withdrawal of an adjacent ring of the wire.

In testimony whereof I have signed my name to this specification.

WILLIAM H. BORDEN.
